DESIGN FOR A WINDOW DEFROSTING NOZZLE

George R. Wallen and Herbert R. Trausneck, New York, N. Y., assignors to Anemostat Corporation of America, New York, N. Y., a corporation of Delaware

Application December 4, 1944, Serial No. 116,691

Term of patent 7 years

(Cl. D62—2)

To all whom it may concern:

Be it known that we, George R. Wallen and Herbert R. Trausneck, citizens of the United States, residing at New York city, in the county of New York and State of New York, have invented a new, original, and ornamental Design for a Window Defrosting Nozzle, of which the following is a specification, reference being had to the accompanying drawing, forming part thereof.

Figure 1 is a front elevation of a window defrosting nozzle showing our new design.

Figure 2 is a rear elevation thereof.
Figure 3 is a side elevation thereof; and
Figure 4 is a top plan view thereof.

We claim:

The ornamental design for a window defrosting nozzle, substantially as shown.

GEORGE R. WALLEN.
HERBERT R. TRAUSNECK.
